BY Goepel & Baeguer,

ATTORNEY.

UNITED STATES PATENT OFFICE.

FREDERICK BRINK, OF BROOKLYN, NEW YORK.

SAFETY-NOZZLE FOR KEROSENE-CANS.

SPECIFICATION forming part of Letters Patent No. 415,609, dated November 19, 1889.

Application filed September 20, 1889. Serial No. 324,508. (No model.)

To all whom it may concern:

Be it known that I, FREDERICK BRINK, of Brooklyn, in the county of Kings and State of New York, a citizen of the United States, 5 have invented certain new and useful Improvements in Safety-Nozzles for Kerosene-Cans, of which the following is a specification.

The object of my invention is to provide a 10 new and improved safety-nozzle for kerosene-cans which is so constructed that in case the gases escaping from the nozzle of the can become ignited they automatically close a valve in the nozzle, thus preventing the 15 gases from igniting the oil in the can.

The invention consists in a spout for cans, composed of a tube projecting from the can, a chamber at the end of said tube, an outlet-tube at the outer end of the chamber, a valve 20 hinged at the top of the inner end of the chamber to automatically close the tube extending from the can to said chamber, and a vent-tube in the top of the chamber of the valve.

25 In the accompanying drawing a vertical cross-sectional view of a can provided with my improved nozzle is shown.

On the end of the spout A the enlargement or chamber B is formed, and from that end of 30 the same opposite the one connected with the spout A the outlet-tube C projects. On the top part of the inner end of said chamber B the valve D is hinged in such a manner as to close that end of the spout A connected with the chamber B. A curved wire E projects 35 upward from the outer side of the valve E, so as to strike against the top of the chamber B and prevent the valve from being opened too far. A vent-tube F is provided in the top of 40 the chamber B, above the valve, for the escape of the gases.

It is well known that as long as kerosene is being poured into the fire no explosion will take place; but the moment that the stream 45 is interrupted the gases remaining in the nozzle catch fire and ignite the contents of the can.

The valve D of my improved spout is so arranged that as soon as the spout is raised to stop the flow of oil the valve D swings 50 against its seat, thereby closing the upper and outer end of the tube-spout. In case the gases in the outlet-tube C become ignited the pressure of these gases forces the valve D against its seat, thereby preventing the flame 55 from passing through the tube A into the can, and the gases can at once escape through the vent F.

It is evident that this improved spout can be used on cans containing alcohol, benzine, 60 varnish, or other highly-inflammable substances as well as on kerosene-cans.

Having thus described my invention, I claim as new and desire to secure by Letters Patent—

1. In a spout for cans, the combination, 65 with a tube projecting from the can, of a chamber at the end of said tube, an outlet-tube at the outer end of said chamber, a valve hinged at the top of the inner end of the chamber to automatically close the tube 70 extending from the can to said chamber, and a vent-tube in the top of the chamber above the valve, substantially as set forth.

2. In a spout for cans, the combination, 75 with a tube projecting from the can, of a chamber at the end of said tube, an outlet-tube at the outer end of said chamber, a valve hinged at the top of the inner end of the chamber to automatically close the tube 80 extending from the can to said chamber, a vent-tube in the top of the chamber for the valve, and a curved check-wire projecting from the outer side of the valve and adapted to strike the top of the chamber to prevent the valve being opened too far, substantially as set 85 forth.

In testimony that I claim the foregoing as my invention I have signed my name in presence of two subscribing witnesses.

FREDERICK BRINK.
